SETTEE OR SIMILAR ARTICLE

Morris Futorian, Glencoe, Ill.

Application March 21, 1955, Serial No. 35,121

Term of patent 7 years

(Cl. D15—11)

The single drawing figure is a perspective view of a settee or similar article showing my new design.

The opposite side of the settee or similar article is the same in appearance as the side shown and the back of the settee or similar article is substantially plain.

The broken away portion shown in the drawing is to indicate indefinite length.

I claim:

The ornamental design for a settee or similar article, as shown and described.
